[57] CLAIM

The ornamental design for a combined water closet and seat, substantially as shown and described.

DESCRIPTION

FIG. 1 is a front elevational view of a combined water closet and seat embodying my new design;

FIG. 2 is a left side elevational view thereof, the right side being a mirror image of the left side shown;

FIG. 3 is a top plan view thereof;

FIG. 4 is a bottom plan view thereof;

FIG. 5 is a rear elevational view thereof.

FIG. 1

FIG. 2

FIG. 3

FIG. 4

FIG. 5
